United States Patent Office

Des. 184,518
Patented Mar. 3, 1959

184,518

CUP

Donald E. Folley, Fayetteville, N. Y., assignor to Onondaga Pottery Company, Syracuse, N. Y., a corporation of New York

Application January 18, 1955, Serial No. 34,041

Term of patent 14 years

(Cl. D44—9)

Fig. 1

Fig. 2

I claim:

The ornamental design for a cup, as shown.
